UNITED STATES PATENT OFFICE.

MAX BORNKESEL, OF NEW YORK, N. Y.

HEATING-UNIT ADAPTER.

Application filed June 9, 1927. Serial No. 197,752.

This invention relates to hair dressing apparatus and more particularly to curling devices.

Such devices are extensively used by 5 women and are especially in vogue in hair dressing establishments which cater to their trade, being disposed on the apparatus in multiple formation and it is therefore desirable that they be arranged for convenient 10 and rapid handling.

One of the objects of this invention is to provide an adapter for the sockets of curling units enabling ready and easy handling of the individual implements.

15 A further aim is to provide means whereby the unit and adapter are positively engaged to present a firm structure preventing accidental displacement.

These and other objects, such as simplicity, lightness in weight, low cost of production and design of a unitary element, hereinafter delineated and depicted in the accompanying illustration, form an important component of this disclosure, and in 25 which:

Fig. 1 is a longitudinal sectional view of an adapter made in accordance with this invention, as applied to a conventional heating unit.

30 Fig. 2 is a perspective view of the same in detail.

In the drawing, the numeral 5 generally designates a standard type of cone-shaped heating unit or socket having a cylindrical longitudinal bore and being provided with 35 an asbestos covered loop 6 from which emerges a cable 7 connected to a source of electrical energy, this socket containing high resistance coils and constituting a heater, all of the foregoing being of well known 40 construction and constituting no part of the invention.

The adapter consists of a light, thin-walled metal tube 8, made preferably of aluminum, and provided, approximately 45 midway in its length, with an integral outstanding bead 9.

The lower portion of the tube contains a plurality of uniformly spaced parallel slots 10, extending from the end nearly to the 50 head 9, imparting a resilient effect to the tube, the slotted end of which is provided with an outwardly projecting curved, annular flange 11, the distance between the bead and flange exactly equalling the length of 55 the heater socket.

The slotted end portion of the tube is

entered into the bore of the heater 5 until the bead 9 contacts against the top of the heater and the flange 11 springs outwardly from the bottom of the same, due to the 60 resiliency of the tube thus confining the adapter within the heater, but permitting it to be removed upon the application of force sufficient to contract the tube by partially closing the slots. 65

During the hair curling operations, the hair is first wound about a core and is then covered with thin steam pads coiled over the hair, these pads being moistened with water or any preferred solution. The whole is 70 placed in the tube 8 through the slotted end portion.

The electric current is then applied for time intervals depending upon the degree 75 of curling or effect desired.

In removing the adapter, the upper part of the tube 8 is used as a handle and by force, withdrawn from the heating socket.

Thus, by means of the bead 9 and flange 11, the adapter is held rigidly in the unit 5 80 until it is desired to withdraw the same and is obviously interchangeable.

Although the foregoing is descriptive of the preferred embodiment of the invention, it will be apparent that minor changes may be made in its construction, without the exercise of invention or conflicting with the scope of the claims hereto appended. 85

Having thus described my invention, what I claim as new and desire to secure by Letters Patent, is:—

1. An adapter for electric curling devices comprising in combination with a heating unit, a tube, an extruded bead on said tube, and resilient means at one end of said tube to firmly engage the heating unit, when fully entered therein. 95

2. An adapter for electric curling devices comprising in combination with a heating unit, a tube engageable in the heating unit, and means on said tube to resiliently lock the same when in engagement within the heating unit. 100

3. An adapter for electric curling devices comprising in combination with a heating unit, a tube engageable in the heating unit, an extruded bead on said tube to limit the engagement of the same with the heating unit, and an annular flange on the engaging end of said tube to retain the latter in a firm position within said unit. 105

4. An adapter for electric curling devices comprising in combination with a heating

unit, having an axial bore, an elongated, cylindrical tube, close fitted to the bore, the entering portion of said tube being longitudinally slotted, an extruded bead midway in the length of said tube beyond the slots to limit its engagements with the unit, and an outwardly projecting, annular flange on

the slotted end of said tube to engage the opposite end of the unit to retain the adapter firmly therein.

Signed at New York, county of New York, and State of New York, this 13th day of May, 1927.

MAX BORNKESSEL.
